UNITED STATES PATENT OFFICE

JOHN GOOD, OF BROOKLYN, NEW YORK, ASSIGNOR TO GOOD INVENTIONS CO., OF BROOKLYN, NEW YORK, A CORPORATION OF NEW YORK.

COMBUSTION-ENGINE.

1,377,990.

Specification of Letters Patent.

Patented May 10, 1921.

Application filed February 21, 1917, Serial No. 149,998. Renewed March 23, 1920. Serial No. 368,158.

To all whom it may concern:

Be it known that I, JOHN Good, a United States citizen, residing in Brooklyn, New York, have invented the following-described

5 Improvements in Combustion-Engines.

The invention is an improved means for operating and starting internal combustion engines, particularly those intended for use on relatively heavy fuels, such as low grade 10 gasoline, kerosene and like motor fuels, and also for starting engines using any kind of fuel in cold weather and consists in an organization of flame-producing mechanism combined with the normal charge-proportioning mechanism whereby the suction effect created by cranking the engine, by hand or motor, produces instantaneous preliminary and non-explosive combustion, the heat of which is applied to the engine charge to 15 vaporize it and thereby enables the engine to take up or continue its normal operation. The invention includes the vaporization of the engine fuel mixture, in part or whole, by direct contact with the hot combustion 20 products from a continuous flame, or with the flame itself, and also, by the preheating, by such flame, of the passage through which the mixture flows to the engine, or the container of such mixture or of the fuel. The 25 invention also includes the organization of the independent combustion apparatus whereby it is available for heating the fuel or any part of the engine where heat is required, after the engine is running, as for 30 example when the fuel is not sufficiently vaporized by the heat developed by the combustion process of the engine itself. The invention further includes various details of structure and operation hereinafter made 35 apparent and which may or may not be employed to carry out the principle of the invention but which are nevertheless important in their several respective functions and are herein broadly claimed.

40 In the drawings:

Figure 1 is a side elevation of a conventional type of engine illustrating the exhaust and inlet headers in longitudinal section with an independent heating apparatus incorporating this invention;

Fig. 2 is an enlarged section of the charge proportioner and burner head of Fig. 1;

Fig. 3 a diagram of the electric wiring of Fig. 1;

Fig. 4 an engine with an exhaust header

and vaporizing tube in longitudinal section and a modified application of the supplemental combustion means;

Fig. 5 shows in larger scale the suction burner head of Fig. 4;

Fig. 6 is a modified type of head;

Fig. 7 a cross-section of Fig. 6; and

Figs. 8 and 9 are a modification showing a different use of the flame and an illustrative form of interlock between the burner head and charge-forming apparatus.

Referring first to Figs. 1-3, the multi-cylinder engine taken for illustration is equipped with an exhaust heated fuel charge vaporizer and may be assumed to be representative of the type of engine which uses heavy fuel, though without limitation to such type. Its exhaust ports 1 and intake ports 2 are on the same side of the cylinders and the suction intake passage is constituted of the charge proportioner or carbureter 3, the elbow 4, the vaporizing tube 5 and the inlet header 6. The vaporizing tube is a thin Venturi tube extending in the present case from end to end of the exhaust header 7, the heat in which serves to vaporize the fuel in the tube under normal conditions of engine operation. This style of vaporizer is specially suited for engines using fuel of the grade of kerosene but forms no part of the present invention which is adapted for use with any kind of engine as above stated.

The charge proportioner or so called carbureter will be recognized as of conventional type comprising a fuel nozzle 8 supplied with fuel from a float chamber 9 and having primary and secondary air inlets 10 and 11 respectively and a usual choker 52. The liquid fuel nozzle will be understood to be correlated to the primary air inlet 10 and to the valve spring of the secondary inlet 11 so as to keep the charge mixture delivered to the engine within the limits of an explosive mixture, as customary in engine carbureters. These fuel and air entrances, however arranged for this purpose, constitute a charge mixture supply device adapted to give a variable delivery of charge mixture to the engine, according to the manipulation of the throttle 12. The choker valve 52 may be closed as usual in order to give an overrich charge mixture to the engine.

The supplemental combustion apparatus comprises a suction-operated flame-producing device or burner head 13 discharging its

flame and combustion products, through a flame tube 14 into the suction intake of the engine, preferably on the inside, or the engine side, of the throttle 12 and desirably 5 through a restricted outlet such as constituted by the rotary plug valve 15. The flame tube 14, so connected between intake and burner head, may be variously related to the engine or its charge-forming apparatus for the purposes of this invention and 10 as will later appear. In Fig. 2 it is coiled around the spray nozzle 8 of the carburetor, in Fig. 4 the corresponding flame tube 14^a leads straight into the suction intake on the inside of the engine throttle; in Fig. 8 the tube is short and leads to a combustion cavity in the carburetor and other methods of utilizing its heat will be obvious. The burner head in Figs. 1 and 2 comprises a 15 main casing or body formed with a nozzle cap 13^a central thereto and in which are mounted a liquid fuel nozzle 16 and an air nozzle 17 in aspirating relation to it. The said air nozzle is merely a restricted entrance 20 for atmospheric air. The fuel nozzle 16 delivers liquid fuel from a constant level fuel receptacle 18 (supplied with the same fuel as used by the engine) at a rate proportional to the velocity of the air jet flowing from 25 the air nozzle 17 but subject to adjustment by its needle valve 19. The fine spray produced by these nozzles is ignited by a pair of single pole spark plugs 20, the electrode terminals of which extend convergently 30 downward from cavities in the upper part of the nozzle cap directly into the spray and are there bent convergently upward, like hooks, as shown at 21 in Fig. 7. The electrodes are thus directly in the path of the 35 liquid spray but liquid impinging thereon is drained away from the gap by virtue of the hook shape, and thereby short-circuit of the gap by liquid is prevented, and in consequence, ignition may be reliably accomplished by current of low value. As shown 40 in Fig. 2 the upwardly convergent terminals of the electrodes are also bent slightly toward the spray nozzle so that the blast from the spray will help drain away the impinging liquid. The self-draining shape of the 45 electrodes is particularly desirable where the engine fuel used is kerosene, or where they are operated by moderate current.

Prompt electric ignition of the mixture, 50 even though in a cold state, is accomplished by the fine shattering of the fuel liquid and its mixture with air, which is the principal function of the nozzles 16 and 17 and which effect is enhanced by the fact that the air 55 passage receives air at atmospheric pressure or at least considerably higher than exists in the mixture passage of the intake.

Air to support combustion of the spray is 60 admitted into contact with it immediately beyond its point of ignition and in such man-

ner as to avoid dilution of the spray at that point. Dilution of the spray at the igniter may prevent ignition completely or produce explosion, as later explained. In Fig. 2 a cylindrical perforated shell 22 of thin metal 70 surrounds the spray just in advance of the igniter and divides the interior of the head into a central spray or ignition and mixing space and a surrounding annular admission chamber. Atmospheric air enters this chamber through a spring-loaded check valve 23 and flowing through the perforations in the shell is thus brought into contact with the spray uniformly on all sides and without interfering with the proper ignition. The 75 adjustment of the check valve spring, which is a tapered coil spring, in relation to the orifice of the air nozzle 17 assists in establishing the requisite velocity in the latter and the proper volume of flow through the 80 former to create and maintain certain pre-determined rates of inflow of fuel and air quite the same as in the carburetor, so as to produce continuous and substantially complete combustion throughout the combustion 85 range of the device. The shell 22 is connected to the flame passage by a convergent imperforate connecting section 24, and a drain hole 41 may be provided in the bottom 90 of the burner to return to the receptacle 18 any drip of liquid fuel. Such hole also establishes equality of pressure between the ignition space and receptacle. The spark 95 plugs 20 are connected in any suitable igniting circuit such as indicated diagrammatically in Fig. 3, and which, for example, shows them connected to the secondary of a 100 vibrating spark coil 25 the primary of which is supplied from a battery which may be assumed to be a storage battery of the igniting 105 and lighting system of an automobile. Such circuit is controlled, in Figs. 1 and 2, primarily by a circuit closer 26 but does not become active until its two terminal contacts 27 are electrically connected by the 110 rotary switch plate 28, which plate is mounted on, or moved with, the rotary plug valve 15, and in such relation thereto that the circuit is completed whenever the said plug valve is 115 opened. The said valve is connected by linkage 29, or in any other suitable way, with the engine throttle 12 and so that when the latter is closed, or nearly closed, the valve 15 will put the burner head 13 in direct communication with the suction intake 120 of the engine.

Assuming said valve to be open and the engine to be cranked over by hand or by using the starting motor 30, (Fig. 1,) the suction effect thereby established and communicated to the burner head, will cause a high velocity air jet to enter it through the nozzle 17 inducing a fuel spray from nozzle 16 and a current of larger volume to enter it through the valve 23. The spray first 125

encounters the spark and is ignited and immediately joins the air current and a continuous flame is thereby produced extending into or through the flame tube and of 5 greater or less intensity according to the suction produced by the engine. The particular arrangement of burner parts as above described, produces a mixture condition which not only permits instant and 10 non-explosive ignition, even of kerosene fuel, but also positively controls the mixture proportions after ignition and regardless of change of the strength of the suction, which latter affects only the rate of 15 combustion, or flame delivery, as stated. The mixture proportions during combustion are those of an explosive mixture and result in a steady, clean-burning flame. Explosion does not result from ignition be- 20 cause the spark occurs in a relatively rich mixture, too rich to explode, though capable of igniting and continuing the inflammation.

Thus the mere cranking of the engine 25 with the ignition circuit closed automatically creates a continuous heated flow through the intake and engine passages, heating them and eventually escaping through the normal exhaust, and thereby 30 the coiled part of the flame tube 14 around the spray nozzle 8 in Fig. 2, will become highly heated becoming in fact a bright red in a few seconds. If the throttle 12 is now opened to communicate the engine suction 35 to the carburetor and induce an air flow through the primary inlet 10, the fuel spray from the nozzle 8 will be discharged into a highly heated region, or into direct contact with the heated coil, and becoming 40 thereby vaporized, will pass to the engine as an explosive mixture more or less completely vaporized. Beyond the throttle 12 this charge mixture may encounter the hot gases from the flame tube 14 to be further 45 heated or vaporized by such contact. As will later appear in connection with Figs. 7 and 8, the throttle 12 may be partly open when the burner comes into action. Relatively large amounts of flame products 50 from the tube 14 may be introduced into the initial engine charges without impairing their explosive qualities for starting or even for running the engine. The linkage 55 may therefore be designed so that the flame tube is not entirely shut off until after the throttle is well open or opened to some predetermined extent at which the engine is sure to have been well started, this mechanical control being obviously additional to 60 the control of the combustion rate which is effected by the change or diminution of the strength of the engine suction. The closing of the valve plug 15 stops the combustion in the burner head by discontinuing 65 the suction. Such closing may be done

gradually with no other effect than to diminish the intensity of the flame down to a point where the inflowing air jet is incapable of discharging the liquid from the fuel nozzle. Immediately on re-opening the 70 valve 15 the combustion will be resumed automatically by the effect of the suction produced by the combustion operation of the engine, it being apparent that the independent combustion can be used to supplement 75 the normal engine heat whenever and to whatever extent desired. The particular linkage mechanism shown in Figs. 1 and 2 is merely illustrative of one form of mechanical control, so designed that if the 80 throttle be brought to a partially closed condition after a period of running, the supplemental heat will then be automatically started, to make up for any deficiency in the temperature of the engine's exhaust for 85 fuel vaporizing purposes. Certain types of kerosene-burning engines having exhaust heated vaporizers do not deliver sufficient exhaust heat when idling to continue proper 90 vaporization and this form of linkage control is suitable for these engines. Another type of control is shown in Figs. 8 and 9. It will be understood however that the manner of control whether automatic or manual, is susceptible of wide variation and 95 that the supplemental suction-induced combustion may be variously applied to the engine and also that the flame tube may serve to heat any other part than the carburetor proper. 100

In Figs. 4 and 5 the general engine construction will be recognized without explanation. The burner is mounted on the intake header above the level of the carburetor, which is found in practice to have special 105 advantage in automotive equipment. The flame tube 14^a in this case runs straight into the vaporizer tube 5^a from the elbow 4^a and is controlled by a throttle 30 at its junction with the burner head. This throttle is 110 opened by a pull rod 31 and when so opened the throttle lever closes the circuit of a magneto generator 32 as indicated by the diagram, so that the spark plugs are thereby connected. Inasmuch as the magneto will 115 be in action when the engine is turning over, sparking current will be produced simultaneously with the suction produced by the engine rotating means, and combustion will thereby be automatically established as 120 already described. The engine throttle 12 in this form is assumed to be independently operated. The burner head of this form is identical with that already described excepting that the air and fuel nozzles 33 and 34 are each formed of two thimbles of identical size and shape and having flanges at their base ends which are clamped against the ends of the tubular bosses 35 and 36, cast on the burner head body. 125 130

The burner head shown in Figs. 6 and 7 is similar in function to those already described, the fuel shattering means and the igniter being identical in form and arrangement with the same parts appearing in Fig. 2. The supplemental or combustion supporting air is in this case drawn into an air admission chamber 37 in rear of the air nozzle 17, through a spring-loaded valve 10 38, and enters into contact with the ignited spray through a series of holes 39 and between the wings of a star-piece partition member 40, being thus brought into contact with the spray uniformly on all sides thereof and without diluting or distorting it at its point of ignition.

In Figs. 8 and 9, the coil of pipe shown in Fig. 2, is replaced by a combustion cavity 42 connected to the burner head and opening 20 into the suction intake above or inside of the throttle, at 43. The wall 44 of course becomes highly heated by the flame from the burner. In this apparatus the relation of the liquid orifice to its associated air orifice 25 serves to maintain the predetermined proportions of fuel and air in the burner besides serving as the shattering means for the liquid fuel. Control of the burner is in this case by the turn valve 45 which controls 30 the entrance thereto of both airs, that is, of the atomizing air and combustion supporting air, and which, like the valve 15, may also control the ignition circuit, if desired. This valve is arranged to be operated by its 35 link 46, crank arm 47 and rod 48, by a pedal or hand lever 49, which may be assumed to be mounted on the dash of an automobile. The hub 50 of the crank arm 47 is interlocked with the hub 51 of the engine throttle 40 12 by the circular cut-out formations of each of them, which will be seen to be so arranged that the throttle cannot be widely opened until after the lever 49 has been set to close the turn valve 45 and stop the burner. By such means the operator is compelled to close or nearly close the throttle before he can start the burner, and to stop the latter before he can open, or further open the throttle, this arrangement being 45 useful in gasoline engines to avoid waste of fuel by failure to stop the burner and to insure adequate suction for starting the burner. In all of the cases above described the combustion device is automatically ignited in the sense that, with the ignition circuit closed, the mere effect of the engine suction establishes the burner flame without any preliminary attention or manipulation on the part of the operator.

50 The control of the relative proportions of fuel and air drawn into the flame-producing device, so that they are substantially constant during its use as above described, exercises the important effect that the combustion is clean and that the admission of the

resulting combustion products to the flow of charge mixture proceeding from the carbureter to the engine in variable amounts, does not change the proportions of fuel and air in the mixture which enters the engine, as 70 would be the case, for example, if the burner mixture grew excessively rich or lean on increasing or decreasing suction delivery. And by controlling the burner proportions so that they are always within the general 75 limits of explosive mixtures, as above described, the burner may be turned on or off whenever desired, without effect on the proportions of the mixture entering the engine, thus providing for, or accommodating, the 80 automatic functioning of the burner for any part of the operating range of the engine or the delivery range of the carbureter. With explosive proportions the products of combustion contain no appreciable excess of fuel 85 or air, which if added to the carbureter mixture might alter its proportions or render it unsuitable for efficient combustion in the engine especially at idling, or require a re-adjustment of the carbureter whenever the 90 burner is in operation. Thus by reason of such control the apparatus herein described is capable of operation on an automatic basis and thereby adapted for use on automobile and like variable speed engines which may 95 require supplemental heat intermittently and more at one time than another. In some forms of this invention, the flame may extend through the flame tube into the intake passage and does so without inflaming 100 the mixture and such use of this invention obviously gives the most rapid vaporization of the liquid fuel in that mixture although, as stated, there is no limitation to the manner of use of the supplemental combustion. 105 Reference to this phenomenon is made merely to indicate the scope of the invention and the flexibility of its mode of operation.

The apparatus above described incorporates certain principles of structure and operation disclosed and claimed in my previously filed application Serial No. 101,889, filed June 6, 1916, and the method of starting and operating internal combustion engines according to the principles of this 115 invention is also disclosed and claimed in other copending applications.

Claims.

1. In combination, an internal combustion engine having a throttle-controlled suction 120 intake including a carbureter delivering charge-mixture-proportions, and an automatically-igniting burner connected with said intake and having fuel and air admission means functioning by the suction of 125 said intake to maintain relative proportions serving to support a continuous flame within itself, and an outlet from said burner adapted to deliver the burner products into said intake by the effect of the suction there- 130

in for supplying heat to vaporize the engine fuel.

2. In combination, a variable-speed internal combustion engine having a throttle-controlled suction intake including a carbureter and an automatically-igniting burner connected with the suction intake and comprising controlling means for the admission of liquid fuel and air thereto automatically 10 functioning by the suction effect in said burner to preserve substantially constant relative proportions of said fuel and air and adapted to burn the same at a variable rate according to variation of said suction effect.

15 3. The combination of an internal combustion engine and its normal charge-mixture supply apparatus, a source of flame provided with an orifice emitting liquid fuel, a coaxial air flow passage and an igniter 20 all automatically rendered operative when subjected to the suction of the engine, said apparatus and flame source being both connected to the engine and adapted for coincident operation to deliver the output of 25 said source together with normal engine mixture to the engine.

4. The combination of a multi-cylinder internal combustion engine provided with apparatus for producing an igniting current, a charge-mixture supply device operated by the engine suction, a burner for furnishing heat to said mixture supplied with fuel and air by the effect of said suction and comprising means for maintaining predetermined rates of inflow thereto of fuel and air respectively and an electric igniter in 30 said burner operated by said current, said burner being adapted to produce flame automatically when subjected to said suction 35 and current.

40 5. The combination of a variable-speed, multi-cylinder internal combustion engine, a device adapted to deliver charge-mixture thereto at variable rates of flow and a variable delivery flame-producing device for imparting heat to the charge mixture, comprising suction-operated means for supplying substantially constant proportions of fuel and air to said device throughout varying 50 rates of delivery of the other device.

6. The combination of a multi-cylinder internal combustion engine having a suction intake passage, a charge-mixture device having a variable delivery rate, a flame-producing device containing an igniter, both devices being connected to said passage and adapted to be coincidently operated by the suction therein, means for automatically establishing an ignitable mixture of fuel and air in the latter device, said means including air and fuel supply passages relatively so restricted as to maintain predetermined proportions in said mixture when in normal combustion and independently of the rate 60 of mixture delivery of the other device.

7. The combination of an internal combustion engine, a charge-mixture-forming device, and a flame producing device coincidently operated by the engine suction and the latter device serving to supply heat to 70 the engine charge, each device having automatic means whereby its mixture of fuel and air is constantly maintained of explosive proportions during its normal operation and means including an igniter for automatically initiating combustion in said flame device.

8. The combination of a variable speed internal combustion engine, a charge-forming device and an automatic flame-producing device both operated by the suction effect of the rotating engine and the latter device serving to supply heat to the engine charge, the combustion range of the latter device being limited to a part of the range 80 of the other device, and means for maintaining controlled proportions of the fuel and air in said latter device throughout its 85 said combustion range.

9. The combination of a variable speed 90 multi-cylinder internal combustion engine having a charge-mixture device, a flame-producing device associated therewith and adapted to supply heat to the engine fuel and containing an electric igniter, both devices being adapted to be coincidently operated by the engine suction, means for automatically establishing an ignitable mixture of fuel and air in the latter device, said means including air and fuel supply 95 passages relatively so restricted and controlled as to maintain substantially constant proportions in said mixture when in normal combustion, said two devices being mutually related whereby the flame-producing device 100 functions only during the predetermined portion of the range of operation of the other, and means operated coincidently with the engine for delivering an igniting current 105 to said igniter.

110 10. The combination of an internal combustion engine, a suction intake passage, a charge-mixture device and a flame-producing device arranged to supply vaporizing heat to said passage and provided with 110 means adapting it to burn with a continuous flame at varying rates of combustion, both said devices being connected to and operated by the suction of said passage and mutually related to decrease the combustion 115 rate of the last mentioned device coincidently with increase of delivery rate of the other device.

120 11. The combination of a multi-cylinder internal combustion engine having a rotating means for starting it, a charge-mixture device and a flame-producing device, both connected for operation by the suction of the engine, the latter device comprising means functioning by the suction produced by said 125 130

rotating means for establishing within itself an ignitable mixture of fuel and air and adapted to maintain continuous flame in said device, an electric igniter for said device 5 automatically energized upon the operation of the engine starting means, said two devices being correlated whereby the act of starting the engine automatically creates flame in the one for imparting heat to the 10 mixture produced by the other.

12. The combination of an internal combustion engine having a rotating means for starting it, a suction intake passage, a charge-forming device and a flame-producing 15 device both connected to said passage, the latter device comprising air and fuel passages automatically coaxing to produce an ignitable mixture therein by the suction created by said rotating means, and adapted to 20 deliver its continuous flame output to said intake during the combustion operation of the engine, and an igniter in said device adapted to function coincidently with the operation of said rotating means whereby 25 said flame-producing device imparts heat to the intake before and after the engine picks up.

13. The combination in an internal combustion engine having a starting motor and 30 a suction intake including a carburetor provided with a fuel spray nozzle, of a continuous flame burner having its outlet connected to said intake at a point between said nozzle and engine and provided with an entrance passage receiving air at a higher pressure than exists in said intake at any point 35 between said carburetor nozzle and engine, a fuel supply passage coaxing with said air passage to establish a mixture of fuel and 40 air in the burner and an igniter for said mixture adapted to be operated coincidently with the operation of said starting motor, whereby the burner furnishes heat to the intake while said motor rotates the engine.

45 14. The combination in an internal combustion engine having a suction intake including a charge-forming device, of an engine-rotating means and a continuous-flame burner operated by the suction in said intake 50 to heat the engine charge and comprising an igniter adapted for operation coincidently with said rotating means, said burner comprising mixture-producing means functioning by the suction created by said rotating 55 means to establish an ignitable mixture of fuel and air in the burner and functioning to maintain a continuous flame in said burner under the suction effect caused by the idling operation of the engine.

60 15. In an internal combustion engine, a suction intake including a carburetor provided with a fuel nozzle and air admission means adapted to produce an engine-operating mixture, a suction operated burner 65 having its outlet connected to said intake be-

tween the carburetor fuel nozzle and the engine and comprising a fuel nozzle delivering fuel thereto independently of the carburetor fuel nozzle and an air entrance conducting air to said burner independently of the air 70 entering into the mixture produced by said carburetor.

16. The combination of a multi-cylinder internal combustion engine provided with rotating means for starting it, a suction intake 75 and two suction-operated, mixture-producing devices connected therewith, one of said devices containing an electric igniter, and adapted to produce a continuous flame and deliver its hot gases to the intake and 80 each device comprising independent means for normally maintaining its mixture proportions within the limits of explosive mixtures, whereby the engine receives explosive mixture proportions independently of the 85 functioning or non-functioning of said flame-producing device.

17. The combination of a multi-cylinder internal combustion engine of the automobile type adapted to operate under load at 90 variable speeds, a charge-mixture device, a variable delivery, flame-producing device containing an electric igniter, both devices being adapted to be operated by the suction 95 of the engine whereby hot flame products are delivered to the engine together with engine charge mixture, means for automatically establishing an ignitable mixture of fuel and air in the latter device when the engine is cranked over for starting, said 100 means comprising air and fuel supply passages relatively so restricted and controlled as to maintain predetermined proportions in said mixture when the engine is in combustion operation and means adapted to be 105 operated coincidently with the rotation of the engine for energizing said igniter.

18. In an internal combustion engine, the combination of a charge-mixture-supply device and an automatic flame producing device both delivering to the intake passage of the engine, the latter device comprising an ignition space, an igniter, means automatically operated by the engine suction for establishing an ignitable mixture of fuel 110 and air in said space and adapted to control the mixture proportions of fuel and air entering the same, and a relatively restricted outlet from said space through which the products of said flame-producing device pass 115 to the intake.

19. In an internal combustion engine, the combination of a charge-mixture-supply device therefor, a flame producing device, both connected to the said suction passage of the engine and the latter being organized to admit flame into contact with the fuel delivery of the other device and thereby non-combustibly vaporizing the same.

20. The combination of a multi-cylinder 130

internal combustion engine having a rotating means for starting it, a suction intake passage, a charge-forming device having a liquid fuel orifice, a flame-producing device, 5 both devices being connected to said passage and the latter device comprising an ignition space, means operated by the suction in said passage for automatically establishing an ignitable mixture of fuel and air 10 therein, an igniter in said device adapted to be energized coincidently with the operation of said rotating means and a passage conducting flame from said space into contact with the liquid fuel discharged from 15 said orifice.

21. In an internal combustion engine, the combination of a carbureter fuel nozzle and air admission means coacting to produce an engine-operating mixture of fuel spray 20 and air, a suction intake to conduct the same to the engine, a combustion chamber adjacent said intake, means whereby a flame is maintained in said chamber, and an outlet from said chamber into the intake adapted 25 for passing said flame into direct contact with said engine-operating mixture and thereby non-combustibly heating said mixture in transit to the engine.

22. In an internal combustion engine, the combination with a carbureter fuel nozzle and air admission means coacting to produce an engine-operating mixture, a suction intake for conducting said mixture to the engine and a throttle to control the flow of 35 said mixture, of a suction-operated flame-producing device having its suction outlet connected to said intake between said throttle and engine and adapted to pass flame directly into contact with the mixture there- 40 in and thereby serving to heat said mixture without inflaming the same.

23. In an internal combustion engine, the combination of a carbureter fuel nozzle and air admission means coacting to produce an engine-operating mixture of fuel spray and air, a suction intake for conducting said mixture to the engine, a suction-operated 45 flame-producing device receiving continuous and substantially constant proportions of fuel and air and organized to maintain a non-explosive flame within itself, and an outlet organized and adapted to pass said flame from said burner into contact with the mixture in said suction intake, thereby non- 50 combustibly heating the mixture in transit to the engine.

24. The combination in an internal combustion engine, of a charge-forming device having a liquid orifice and an air passage 60 leading therefrom to the engine, a combustion device having an ignition space receiving fuel and air and means for controlling the proportions entering the same whereby said device produces continuous flame, and 65 an outlet from said space delivering its prod-

ucts into said passage between said liquid fuel orifice and the engine.

25. The combination in an internal combustion engine, of means for rotating it for starting, means for coincidentally producing 70 an igniting current, a charge forming device having a liquid fuel orifice and an air passage leading therefrom to the engine, an automatic combustion device comprising an ignition space and an igniter energized by 75 said current, and receiving fuel and air by the effect of the suction of the rotating engine, means for controlling the fuel and air proportions entering said space whereby said combustion device produces continuous 80 flame of substantially constant proportions, and an outlet from said space delivering its products into said passage between said liquid fuel orifice and the engine.

26. The combination of a multi-cylinder 85 internal combustion engine having a rotating means for starting it, a suction intake passage, a charge-mixture device provided with a throttle and a flame-producing device, both devices being connected to said 90 passage, the latter device comprising an igniter and means operable by the intake suction for establishing within itself an ignitable, non-exploding mixture of fuel and air and adapted to produce a delivery of 95 continuous flame during the combustion operation of the engine, and a relatively restricted outlet from said device delivering the hot products thereof into said passage between said throttle and the engine. 100

27. The combination of an internal combustion engine having a suction intake passage provided with fuel and air entrances for forming engine charge mixture, a combustion device having coacting fuel and air entrances for automatically establishing a non-explosive ignitable mixture of fuel and air therein, and for maintaining continuous combustion of such mixture, a passage for such flame in heat-transferring relation to 110 said intake passage and a suction connection between said passage and intake.

28. The combination of an internal combustion engine having means for supplying a flow of charge mixture and using engine 115 heat for vaporizing the same, and a flame-producing device capable of continuous non-explosive combustion and automatically brought into action to supply heat to said mixture on a predetermined restriction of 120 said flow.

29. The combination of an internal combustion engine having an exhaust gas pipe, a suction intake including a vaporizer section in heat-exchanging relation to said exhaust pipe, a continuous flame suction burner having its outlet connected to said intake and delivering its hot combustion products into said intake by virtue of the suction in 125 the latter and a charge-forming device coin- 130

- ciently delivering engine charge mixture into said intake for vaporization by said burner products and said vaporizer section while in transit to the engine.
5. 30. The combination with an internal combustion engine using heat for vaporizing its charge mixture of a flame producing device independent of the source of said mixture, operated by the suction effect of the 10 engine and adapted to supply heat to said mixture.
15. 31. The combination with an internal combustion engine using engine heat for vaporizing its normal charge mixture, of a flame producing device independent of the 20 combustion in the engine supplied with controlled proportions of fuel and air and arranged to deliver products of combustion into the charge mixture during the combustion operation of the engine to assist the vaporization of the engine fuel.
25. 32. The combination of an internal combustion engine having a suction intake passage supplied with charge-mixture proportions of liquid fuel and air, an exhaust gas pipe arranged for transferring heat from the combustion in the engine to said passage to vaporize the fuel and a continuous flame suction burner delivering into said passage 30 and automatically diminishing its combustion rate upon increase of fuel supply to the engine.
35. 33. The combination of an internal combustion engine having rotating means for starting it, a suction intake passage receiving heat from the combustion in the engine and provided with means to supply liquid fuel and air to the engine, a flame-producing device automatically ignited by the effect 40 of operating said rotating means and provided with means for supplying controlled portions of liquid fuel and air for combustion therein, and a connection for delivering its products to the intake passage.
45. 34. The combination with an internal combustion engine, its intake passage, charge-mixture supply device, and throttle, of a continuous flame suction burner receiving controlled proportions of fuel and air, 50 an igniter therein and a connection from said space to the said passage located between said throttle and the engine.
55. 35. The combination of a multi-cylinder internal combustion engine having a means for rotating it, a suction intake passage provided with means for supplying charge-mixture and a throttle between said means and the engine, with a suction-operated combustion device communicating with said passage between the throttle and the engine, and means associated with said device adapting it to burn with a continuous flame and at variable rates according to the suction transmitted to it.
60. 36. The combination of an internal combustion engine, a charge-mixture-supply device, and a flame-producing device both connected to, and operated by the suction of the engine, and the latter device comprising means for controlling the proportions of fuel and air burned in it, and means independent of the engine suction for controlling the rate of combustion in said device. 70
75. 37. The combination of an internal combustion engine having a carburetor, a non-explosive flame-producing device adapted to be operated by suction from the engine and valve means whereby said device is connected to a passage leading to the interior of the engine. 80
85. 38. The combination with an internal combustion engine, its suction intake and fuel and air supply means, of a starting motor therefor, a flame-producing device comprising an organization of means receiving and electrically igniting predetermined proportions of air and liquid fuel in a cold state and automatically rendered operative by the action of said motor, and means for conducting its products to said intake. 90
95. 39. The combination of an internal combustion engine having a suction intake with a charge-forming device connected to it and a throttle controlling the charge-mixture, of a suction-operated flame-producing device arranged to heat the charge mixture and having controlling means correlated to said throttle whereby the said flame-producing device is controlled according to the throttle position. 100
100. 40. The combination with an internal combustion engine having a charge-forming device and a throttle controlling the charge therefrom, of a suction-operated flame-producing device having a controlling member and arranged to heat the charge mixture and an interlocking connection between said throttle and controlling member. 105
110. 41. In an internal combustion engine, the combination with the charge forming device thereof, of a flame-producing device, a valve controlling the flow therethrough, an electric igniter for said device and an igniting circuit controlled by said valve.
115. 42. In an internal combustion engine, the combination of a charge-mixture device thereof, a flame-producing device adapted to supply combustion products to the engine and to be automatically put in operation by the suction effect of the engine, and including a liquid fuel inlet, an air-jet nozzle, an inlet for combustion supporting air, and an igniter, and means for supplying the same kind of fuel to both devices. 120
125. 43. In an internal combustion engine, the combination of the suction intake thereof, and a flame-producing device adapted to supply combustion products to the engine and to be automatically put in operation by the suction therein and comprising a suc- 130

tion-operated liquid fuel spraying means, an igniter intercepting the spray and an entrance admitting air to and around the spray beyond the igniter, said means being correlated to maintain in said device the proportions of an explosive mixture.

44. In an internal combustion engine, a flame producing device and a charging forming device both operated by suction in the engine intake and mutually correlated to give coincident deliveries of hot flame products and charge mixture to the engine, said flame-producing device comprising suction means for creating a spray of fuel liquid, an igniter for said spray and means for admitting air to the ignited spray.

45. In an internal combustion engine, inclosed combustion apparatus comprising a flame passage in heat transferring relation to the engine intake passage and connected thereto, a burner head connected to said flame passage and containing a fuel spray inlet, an igniter intercepting the spray and an inlet for combustion supporting air, the said parts being organized to produce ignition and complete combustion within the head and flame passage under the suction effect imparted thereto from the engine intake and during the flow of the engine charge mixture through said intake.

46. In an internal combustion engine, an intake having a throttle regulating the mixture flow from a carbureter to the engine, an inclosed combustion device including an electric igniter and adapted for continuously burning liquid fuel, the outlet from said device being connected to said intake, in combination with throttle connections whereby combustion is established in said device on a predetermined adjustment of the throttle.

47. The combination in an internal combustion engine, of a suction intake, a suction-operated charge proportioning device connected thereto, a suction-operated flame producing device also connected thereto and controlling means for both said devices also controlling the ignition in the latter device.

48. The combination in an internal combustion engine, of a suction-operated charge proportioning device, a suction-operated flame producing device, both connected to the suction intake, and the latter device comprising an electric igniter controlled conjointly with the means connecting it to said intake.

49. An internal combustion engine having an intake passage including a carbureter comprising fuel and air entrances and a choker for the latter in combination with a suction-operated burner comprising means for breaking up liquid fuel to form an ignitable spray mixture adapted to burn non-explosively and having a suction connection with the intake passage between the choker and the engine, whereby the delivery of fuel

to the burner is increased when the choker is closed.

50. In an internal combustion engine, a suction intake including a carbureter comprising a fuel nozzle and air admission means, a suction-operated burner having an outlet for its products connected to said intake, an igniter, fuel and air admission means adapted to produce a mixture of shattered liquid fuel and air therein, said means including a passage leading air from atmosphere to said burner, a choker adapted to restrain the flow of atmospheric air to the carbureter, and a source of current for the igniter adapted to ignite said mixture in a cold state.

51. The combination in an internal combustion engine having a suction intake including a carbureter provided with a fuel spray nozzle, of a suction-operated burner having its suction outlet connected to said intake at a point between said carbureter nozzle and the engine and having means for producing an ignitable mixture of fuel and air including an entrance receiving air at a higher pressure than exists in said intake at any point between said nozzle and engine and an igniter in the burner, said parts being correlated and combined whereby the burner furnishes heat for vaporizing the engine fuel.

52. In an internal combustion engine, the combination of a suction intake including a carbureter, a suction-operated burner having its outlet connected to said intake between the carbureter and engine and having an air entrance receiving air direct from atmosphere under the suction effect transmitted from said intake, a passage for conducting liquid fuel into mixture with said air, an electric igniter in said burner and a source of current therefor adapted to ignite the mixture at its normal or atmospheric temperature.

53. The combination of an internal combustion engine having a suction intake and carbureter provided with a fuel nozzle and air admission means, a suction-operated burner containing an electric igniter and having liquid fuel and air admission means including means for shattering the liquid fuel in the burner organized therewith to permit electric ignition of the fuel in a cold state and to maintain non-explosive combustion therein, and an outlet from said burner to a point in said intake adapted to deliver continuous combustion products from the burner into said intake and a source of current for the igniter adapted to produce said cold ignition.

54. The combination of a multi-cylinder internal combustion engine having a suction intake provided with a fuel nozzle and air admission means operated by the intake suction to make an engine-operating mixture,

- a burner containing an igniter and having liquid fuel and air admission means including means for shattering the liquid fuel in the burner organized therewith to maintain
- 5 a continuous, non-explosive flame therein, said burner being also operated by the intake suction and having its outlet connected to a point in said intake between said fuel nozzle and the engine, whereby the continuous flow of the engine-operating mixture through said intake is joined with, and heated by the continuous suction delivery from said burner during its said operation, and means for supplying the same kind of
- 10 liquid fuel to both said admission means.
55. In an internal combustion engine the combination of a suction intake including a carbureter having a fuel nozzle and air admission means adapted to deliver charge
- 15 mixture proportions, a suction burner containing an electric igniter and having fuel and air admission means including means for shattering the liquid fuel, said shattering means being correlated with the interior burner space to establish a body of relatively rich spray mixture therein which is diluted with air adjacent the wall of said space, and being thereby adapted to maintain a continuous, non-explosive flame with-
- 20 in the burner, an outlet from the burner opening into the said suction intake at a point between the carbureter fuel nozzle and the engine and delivering hot burner products to said intake by virtue of the suction effect in the latter, and a source of current for the igniter adapted to ignite the mixture in a cold state.
56. In an internal combustion engine, a suction intake passage provided with fuel
- 25 and air admission means adapted to produce an engine-operating mixture, a flame space or chamber adjacent to said passage adapted to transmit heat thereto by conduction through the wall thereof and provided
- 30 with an outlet for flame products into the interior of said intake, a suction-operated

burner containing an ignition space and igniter connected with said flame chamber and arranged to project flame transversely into the same against said heat-transmitting wall therein.

57. In an internal combustion engine, a suction intake passage provided with fuel and air admission means adapted to produce an engine-operating mixture, in combination with a flame space, a chamber extending along said intake adapted to transmit heat thereto by conduction through the wall thereof, an outlet near one end of said chamber to the intake passage, and a burner 60 head containing an ignition space connected to said flame chamber near the other end thereof and adapted to be operated by the suction effect therein to deliver flame into and along said space.

58. In an internal combustion engine, a suction intake including a carbureter for producing an engine-operating mixture, a burner having a suction outlet connected to said intake to supply hot products thereto 70 for heating said mixture, means for conducting fuel to the burner, an air valve opened by the intake suction and serving to control the proportions of fuel and air admitted to the burner, and an igniter for the 75 burner adapted for operation coincidently with the operation of the engine.

59. The combination with an internal combustion engine having a suction intake including a carbureter, of a suction-operated burner having an ignition space, connected to said intake, an electric igniter therein, fuel shattering means adapted to produce a fuel mixture therein which is ignitable in a cold state, a chamber containing 85 a body of liquid fuel, a passage for conducting fuel therefrom to said shattering means by the effect of the intake suction and a source of current for said igniter.

In testimony whereof, I have signed this 90 specification.

JOHN GOOD.
